UNITED STATES PATENT OFFICE.

DAVID SMITH, OF WELLESLEY, AND HENRY P. GOLDRICK, OF NATICK,
MASSACHUSETTS.

WATER-TUBE BOILER.

SPECIFICATION forming part of Letters Patent No. 530,664, dated December 11, 1894.

Application filed July 11, 1894. Serial No. 517,180. (No model.)

To all whom it may concern:

Be it known that we, DAVID SMITH, of Wellesley, county of Norfolk, and HENRY P. GOLDRICK, of Natick, county of Middlesex, 5 State of Massachusetts, have invented an Improvement in Water-Tube Boilers, of which the following description, in connection with the accompanying drawings, is a specification, like letters on the drawings representing like parts.

This invention has for its object to provide a novel water tube horizontal boiler, and our invention consists in a boiler comprising top and bottom headers, the former furnishing a 15 steam space above the water line, and water tubes connecting the said headers, substantially as will be described.

Our invention also comprehends the use of water tables or partitions within the boiler 20 with openings therein to cause a circuitous passage of the products of combustion through the boiler to thereby more uniformly heat all the tubes of the boiler.

In the drawings, Figure 1 represents in vertical longitudinal section our invention as applied to a locomotive boiler; Fig. 2, a vertical cross section of the same on the dotted line $x-x$; and Figs. 3 and 4 vertical longitudinal and cross sections of a modified form 30 of our boiler, shown as a stationary boiler, Fig. 4 being a section on the dotted line $x'-x'$ Fig. 3.

Referring to the drawings, in the particular embodiment of our invention there shown, A 35 and B are the top and bottom headers of suitable shape and construction, the same being herein shown as consisting of tube sheets a and b , along the edges of which are suitably secured the edges of the crowning or curved 40 sheets a' , b' . The two headers are joined by a plurality of water tubes c having their ends expanded or otherwise properly attached to the said tube sheets, as best shown in Fig. 1.

In the preferred construction we provide 45 the boiler at regular intervals with water tables or partitions d made hollow, and in open communication at their ends with the top and bottom headers in order that a free circulation of water may be had at all times there-

through, each of the said partitions being provided with a smoke opening d' , shown best in Fig. 2, said openings in successive partitions being staggered to compel a circuitous path of the products of combustion from the furnace D arranged at one end of the boiler, 55 as shown.

The furnace D may be of suitable or desired construction, we having herein shown one surrounded by a water space d^2 and provided with an inclined water table d^3 having a central opening d^4 through which the products of combustion are compelled to pass and be thereby more thoroughly combined and consumed.

F is a steam dome, shown as located immediately over the crown sheet of the firebox, but which may be located farther forward on the top header if desired, or the said steam dome may be omitted.

The sheet d^5 closing the front end of the 70 boiler between it and the smoke arch is shown as provided with a plurality of openings d^6 for the exit of the products of combustion in the smoke arch, thence to the stack d^7 .

Referring now to Figs. 3 and 4, we have 75 shown our invention as adapted for a stationary boiler service, in which H, H', are the top and bottom headers connected by the water tubes h with the interposed water partitions h' provided with the smoke openings h^2 , h^3 , 80 the latter shown only in the section Fig. 4.

In the modification Figs. 3 and 4, the furnace is shown within the corrugated tube m , the products of combustion arising from the fire upon the grate m' passing over the bridge 85 wall m^2 , thence along and into the uptake m^3 , shown as common to two abutting furnaces, from which uptake the products of combustion pass through the several openings h^2 , as shown, and thence into the flue h^4 90 leading to the chimney.

The boiler Figs. 3 and 4 may be set in desired manner.

Our improved boiler presents a very large heating surface, the number of tubes possible to employ being much larger than in the ordinary horizontal tubular boiler. Its flat sides permit a boiler of considerable size to 95

be located between the wheels of a locomotive, the distance between which is restricted by the standard gage of railroads.

The boiler is simple in its construction and 5 possesses great efficiency.

In practice, the sides of the boiler, Figs. 1 and 2, will be inclosed by the side sheets *n*, *n*, and in Figs. 3 and 4, *o*, *o*, said sheets extending between and being secured to the 10 headers, and provided with suitable cleaning openings closed by doors, as shown. The water line is indicated above the tube sheet of the top header, and between it and the 15 crown sheet of the header is a steam space which may be varied in size by changing the shape of said crown sheet.

This invention is, of course, not restricted to the particular construction and proportion of boiler here shown, for the same may be 20 varied without departing from the spirit and scope of our invention.

We claim—

A horizontal boiler comprising top and bottom headers, the former having a steam space above the water level, water tubes connecting 25 said headers, and water partitions interposed between sections of the tubes through which water may circulate from one header to the other, said water partitions being provided with smoke openings staggered in successive 30 partitions to cause the products of combustion to pursue a continuous course and to thereby more effectually impinge upon and heat the faces of said partitions, substantially as described.

In testimony whereof we have signed our names to this specification in the presence of two subscribing witnesses.

DAVID SMITH.
HENRY P. GOLDRICK.
